UNITED STATES PATENT OFFICE.

ALBERT A. GARTHWAITE, OF CONSHOHOCKEN, PENNSYLVANIA.

DESIGN FOR A PNEUMATIC TIRE.

51,370.

Specification for Design.

Patented Oct. 16, 1917.

Application filed August 2, 1917. Serial No. 184,168. Term of patent 14 years.

To all whom it may concern:

Be it known that I, **ALBERT A. GARTHWAITE**, a citizen of the United States of America, residing at North Lane, Conshohocken, in the county of Montgomery and State of Pennsylvania, have invented a new, original, and ornamental Design for Pneumatic Tires, of which the following is a specification, reference being had to the accompanying drawing, forming part thereof.

Figure I, is a perspective view of a tire, illustrating my new design, and

Fig. II, a cross section of the same along the line II, II, of Fig. I.

I claim:

The ornamental design for a pneumatic tire as shown.

ALBERT A. GARTHWAITE.
